GARMENT

Application filed September 3, 1930. Serial No. 479,493.

This invention relates to undergarments of the union suit type and is concerned more particularly with a union suit which is provided with the usual elastic insert at the back and with additional reinforcing means which withstand the strains incident to bending by the wearer and the stretching apart of the edges of the crotch opening.

In union suit undergarments as ordinarily constructed, the back is made of upper and lower sections and between these sections is an elastic insert usually formed of a strip of knitted fabric sewn in position with the wales of the fabric extending horizontally. Such garments are provided with a crotch opening which in the conventional construction extends from a seam of one of the leg portions of the garment upwardly to the insert, the opening lying at one side of the median line of the garment and being normally closed by overlapping portions of the back. In such garments, the stretching apart of the two portions of the back to open the crotch opening imposes a severe strain on the garment at the point where the lower section of the back is connected to the insert and because of that strain, the material of the back is likely to be torn away from the insert near the point where the overlapping portions are connected to the insert.

Also, in such garments with the conventional crotch opening, bending forward by the wearer imposes a strain on the insert which is localized at points spaced on opposite sides of the median line. During such bending, a stretching force is applied to the garment at the two shoulder straps and this force is resisted by the crotch portion of the garment. The strain is imposed along lines which extend from the straps toward the crotch and pass through the insert at either side of the middle of the back, and in the ordinary garment, the elastic webbing is likely to be pulled or torn loose from the back fabric at the points where these strains are applied.

In order to overcome these weaknesses in the ordinary union suit garment, I have devised a garment in which reinforcing means are provided to strengthen the elastic insert

in those areas where the maximum strain is imposed in use. These reinforcements add very little to the material cost of the garment and can be placed and secured in position without increased labor cost. The reinforcements are of elastic material so that their presence does not interfere with free body movement of the wearer and they add greatly to the life of the garment.

For a better understanding of the invention, reference may be had to the accompanying drawings, in which

Fig. 1 is a view of the union suit garment embodying the invention seen from the rear;

Fig. 2 is a front view of the garment with the leg portions folded upwardly to illustrate the crotch construction; and

Figs. 3 and 4 are sectional views on the lines 3-3 and 4-4, respectively, of Fig. 1.

Referring now to the drawings, the garment illustrated is of standard construction and includes a front made up of vertical sections 10 and 11 which overlap to provide the front opening closed by buttons 12. These front portions are cut to provide the usual armholes and neck opening separated by shoulder straps 13. The back of the garment is made in the form of an upper section 14 and a lower section 15, these sections being separated by an elastic insert 16. Ordinarily the upper section of the back is made of two pieces of material stitched together along the middle line 17 of the back and each section terminates in a shoulder strap which is connected to the shoulder strap of the appropriate front section of the garment. The elastic insert is usually made of knitted fabric which is placed so that the wales thereof extend in a horizontal direction, the insert consequently having elasticity in a direction lengthwise of the garment.

In the conventional garment of this type, the lower section of the back is made of two main pieces connected together along the center line 17, and one of these pieces 15a is made of two portions which overlap to provide a crotch opening 18. This opening is somewhat curved and extends from the insert at one side of the median line down to the leg seam 19, and the two overlapping portions of the gar-

ment at the opening are normally kept closed by means of a button and buttonhole at the point 20. In constructing the garment, the two portions of the back which define the opening are placed in position with their edges overlapping and then secured to the elastic insert by suitable stitching along the line 21.

With this construction, it will be evident that to open the crotch opening, the two portions of the back which overlap at the opening must be separated and a strain is thereby likely to be imposed on the garment at the point 22 where the overlapping portions are connected to the elastic insert. Also, when the wearer bends forward, a strain is imposed on the garment at the shoulder straps which is resisted by binding of the garment in the vicinity of the crotch 23. This bending strain causes the elastic insert to stretch and the strains imposed on the insert are localized along lines which extend from the shoulder straps toward the crotch and pass through the insert at either side of the middle line of the back. Because of these strains, the garment is likely, in the course of time, to become torn along the lines of stitching which connect the insert to the main portions of the back.

In order to strengthen the garment in the regions where strains are imposed, I provide reinforcements 24 and 25 placed one on each side of the middle line of the garment and extending across the elastic insert. Preferably the reinforcements are of knitted material and consist of portions of material doubled upon themselves to provide two thicknesses, these reinforcements being secured in place at top and bottom by lines of stitching which secure the insert to the other portions of the back. Preferably the reinforcing straps are secured to the garment only at their top and bottom ends and since they are made of elastic fabric placed with the wales extending horizontally, they do not interfere with the yielding of the insert. If desired, however, the reinforcements may be made by forming plaits in the insert itself. In either arrangement there are three thicknesses of material extending across the insert at the reinforced points.

The reinforcement 24 is placed in vertical alignment with the top of the crotch opening and accordingly lies at one side of the middle line of the back, while the reinforcement 25 is placed on the other side of the middle line of the back. Both inserts lie along the lines of strain imposed on the garment when the wearer bends, and the reinforcement 24 further withstands strains imposed by the separation of the overlapping portions of the garment at the crotch opening. The insert 24 also provides additional thickness of material at the point where the two overlapping portions of the back defining the crotch opening, are connected to the insert, and because of

the additional material, an unusually strong connection can be made between those overlapping portions and the insert. When the portions are pulled apart in use, a severe strain is placed on the stitching by which the portions are held in overlapped relation and connected to the insert and also on the web along the line of stitching. In my new garment, that strain is resisted by the increased strength of the connection made possible by the extra thicknesses of material provided by insert 24.

The reinforcements are preferably made of the same material as the insert and in the construction of the garment, the reinforcements are laid in proper position on the insert and then stitched to the other portions of the back of the garment by the same operations used for the purpose of securing the insert in place. Accordingly, provision of the reinforcements adds but little to the material cost of the garment and practically no additional labor is required.

What I claim:

A garment of the union suit type which comprises a back made up of a top portion and a bottom portion connected by a yieldable insert of knitted elastic fabric in which the wales extend horizontally, said insert extending across the back between the top and bottom portions, said bottom having a crotch opening defined by portions normally overlapping at their edges, said opening terminating at the lower edge of the insert at one side of the median line of the back and substantially in the zone of strain extending from the crotch diagonally to one of the shoulders of the garment, a fabric reinforcement comprising elastic knitted fabric with the wales extending horizontally and having the side edges folded between the reinforcement and the garment, said reinforcement extending in vertical alignment with the end of said crotch opening, stitching connecting the upper edge of the insert and the upper edge of the reinforcement to the top portion of the back and the lower edge of the reinforcement and insert to the bottom portion of the back, affording an additional thickness of material at the place of stitching, and a second fabric reinforcement symmetrically located with respect to said first reinforcement on the other side of said garment and lying substantially in the zone of strain extending diagonally from the crotch to the other shoulder portion of said garment.

In testimony whereof I affix my signature.
ROBERT E. HEYN.
